UNITED STATES PATENT OFFICE

91,103

DESIGN FOR A MOTOR VEHICLE BUMPER BRACKET

Harold B. Donley, Columbus, Ohio, assignor to
Columbus Metal Products Inc., Columbus, Ohio,
a corporation of Ohio

Application September 5, 1933. Serial No. 49,202

Term of patent 14 years

To all whom it may concern:

Be it known that I, HAROLD B. DONLEY, a citizen of the United States, residing at Columbus, in the county of Franklin and State of Ohio, have invented a new, original, and ornamental Design for a Motor Vehicle Bumper Bracket, of which the following is a specification, reference being had to the accompanying drawing, forming a part thereof.

Figure 1 is a perspective view of the bumper bracket showing my new design, and
Figure 2 is a side elevation thereof.

I claim:
The ornamental design for a motor vehicle bumper bracket, as shown.

HAROLD B. DONLEY.
